[57] CLAIM

The ornamental design for a handrail, as shown and described.

DESCRIPTION

FIG. 1 is a perspective view of the handrail of the present invention, showing a section as it might appear in a staircase railing;

FIG. 2 is a top, plan view of the section of FIG. 1;
FIG. 3 is a side, elevational view of the section of FIG. 1, with the opposite side having the same appearance; and

FIG. 4 is an end view of the section.
